UNITED STATES PATENT OFFICE.

CHARLES S. PARKER, OF BOSTON, MASSACHUSETTS.

SAFETY RAZOR.

Application filed April 23, 1921. Serial No. 463,812.

To all whom it may concern:

Be it known that I, CHARLES S. PARKER, a citizen of the United States, residing at Boston, in the county of Suffolk and State 5 of Massachusetts, have invented certain new and useful Improvements in Safety Razors, of which the following is a specification.

This invention relates to improvements in safety razors. Since the advent of the first 10 razor of this type many efforts have been made to improve them, but every type now available, so far as I am aware, is open to objections in the way of multiplicity of parts and expense for machine work in its 15 production, the elimination of which is among the objects of the present invention. And although razors now known are transformable into a knocked-down condition, they are still so bulky as to require carriage 20 in a traveling bag and cannot be put into a sufficiently small space to satisfy the ideal of one whose taste or necessity makes him fastidious in that respect.

It is an object of the invention to meet 25 these means without sacrifice of normal size, rigidity of blade, or of efficiency of shaving qualities. In the complete razor of the invention by which these objects are attained, the holder for the blade has only two parts, 30 one of which provides the guard for the cutting edge, and positions the blade with regard to it, and the other of which coats therewith to retain the blade rigidly, and serves as the handle. The separate parts 35 may be stamped from sheet metal in one operation, and bent to shape in the second operation; so that, aside from finishing or plating, no other work is required in their production. The blade may be of any of a 40 number of standard makes and sizes now on the market, or may be specially designed, with single edge or double edge. The whole, when taken apart, may be packed with the handle, blade and plate in parallelism, sub- 45 stantially within a space required for the plate and its guard edge alone; so small as to mean only an unappreciable shape and weight in one's waistcoat pocket, or on one's key ring.

50 It is intended that the patent shall cover,

by suitable expression in the appended claims, whatever features of patentable novelty exist in the invention disclosed.

In the drawings:

Figure 1 is a front elevation of one embodiment of the invention;

Figure 2 is a side perspective partly in section, on line 2—2 of Figure 1;

Figure 3 is a front elevation of a modification, showing a different style of handle;

Figure 4 is a side elevation of the modification seen in Figure 3, with portions shown in section on the line 4—4 of Figure 3;

Figure 5 is a front elevation showing still another application of the invention, this 65 being in connection with a blade having two cutting edges;

Figure 6 is a side view of the structure of Figure 5, partly in section on the line 6—6 of Figure 5; and

Figure 7 is a plan of the structure of Figure 5, in section on the line 7—7 of Figure 5.

Referring to the drawings, an oblong holder and guard plate 10 is provided by stamping from thin sheet metal of suitable quality and thickness, and by the stamping is provided with an elongated opening 12 along that which is to be its guard edge. In Figure 1 the upper corners are shown clipped, but this is a matter of taste, and the corresponding parts in Figures 3 and 5, are unclipped and in Figure 5 constitute a guard for the second edge of a two-edged blade.

The lower edge of the holder plate is 85 turned backward from the eye, as seen in Figure 1, to form a guard flange 24 by being bent on lines 13 at the end of the opening, and the part of said flange which constitutes the edge of the opening 12 is serrated with 90 guard fingers 16 projecting into the opening.

The opposite side 18 of the opening 12 is a straight edge and, in the finished razor, may be beveled on its front as at 19 to permit the blade to operate close to the surface 95 that is to be shaved. The parts 20 of the plate 10 at the ends of the opening 12 support the flange 24 and are guards which protect the shaver's face from the corners of the razor 28, which lie back of it as seen 100

by dotted lines in Figure 1. At the top edge of the plate 10 is a small flange 22, also bent backward. Lugs 26 may also be turned back in the positions shown in Figure 1 where they engage the side edges of the blade 28 to limit its slipping down and sideways on the holder.

The holder constituted by the plate 10 and its turned back lugs 26 and flange 22 makes a sort of cup into which the blade 28 may be laid when this is held with the flange 22 and lugs 26 projecting upwards. In that case the flange 22 and lugs 26 position the blade in such location that its cutting edge 29 runs along the opening 12 and is exposed through it. It is clamped in that position by the handle 32 which, in the shape illustrated in Figures 1 and 2 is made of a piece of spring bar metal one end of which is bent at 38 into a hook or loop whose end 34 and part 36 next back of the bend 38 constitute the two spring clamping members which embrace the blade 28 and the holder plate 10, pressing them flat together. It is applied by sliding it downward, as the parts are represented in Figures 1 and 2, from the top edge into the position illustrated. To hold the parts firmly together while the razor is in use, the notch 40 is shaped in the outer edge of the guard flange 24, just wide enough to receive the bar of the handle 32, and the handle itself is bent at such an angle from the clamping hook 34, 36, that when the bend 38 of the latter becomes seated in a notch 14 in the flange 22, against the top edge of the plate 10, the shank of the handle 32 becomes seated in the notch 40. So long as the handle bar remains thus seated in the notches 14, 40, it cannot be slipped or twisted sideways, and the whole is secure. Friction tends to hold everything in place because of the clamping; and there is no tendency for the clamp to be displaced upward, because when in use the handle is pulled only downward; and in so far as the parts are subject to any upward pressure of the user's beard or face on the guard 24 or on the cutting edge 29 of the blade, that upward pressure merely tends to seat the two the more firmly within the loop, and to seat the back edge of the blade 28 the more firmly against the top flange of the holder plate. In this position the razor is ready for use. The remainder of the handle 32 may be made in any suitable shape, one shape being illustrated in Figure 2. When thus shaped it is conveniently and firmly held by the user between his thumb placed on the side which is toward the eye in Figure 2, his second finger on the side which is away from the eye, and his first finger in the hollow 33, or bridging across that hollow from the point 35. To take the instrument apart one holds the blade 28 and plate 10 between thumb and forefinger of one hand, and pushes upward

on the handle with the other hand causing the clamping loop 34, 36, 38, to slip off and so leaving the blade 28 free to be lifted or tipped out of the holder.

The modification shown in Figure 3 comprises a form which is similar as regards the general features of the plate 10 and its adaptation to the particular style of blade 28 which is shown in Figure 1, but has a different handle engaging arrangement. In this case the upper flange 22' of the holder plate 10 projects far enough backward, being to the right in Figure 4, to contain an oblong hole 14' into which projects the end 46 of a handle 32' made of flat bar metal. The end which thus penetrates the hole 14' constitutes the fulcrum of a lever which has a bend of about 45° at 47, where it is applied to the flat side of the blade and presses the blade 28 against the plate 10. Further swinging of the lever in the same direction gets it to position where it is latched by engagement with the guard flange 24'. The latter has a sub-flange 50 in which is a recess 49, in which recess is a tongue 48 that constitutes the latch by springing into an opening 31 in the flat bar handle 32'. This latch is constituted by the spring action of the guard flange 24' and adjacent parts 20 of the holder plate 10, which permits the part 24' to be pressed downward to the left as seen in Figure 4 far enough for the tongue 48 to slip into and out of the hole 31 in the handle. For assembling, the parts need only to be put together and pressed together. For taking apart one presses in the proper direction on the flange 24' in order to draw the tongue 48 out of the handle.

Figures 5, 6 and 7 illustrate another modification. In this case the blade 28' has two cutting edges 29' the one which is not set for use being fully protected by lying against the plate 10' as in the case of plate 10 shown in the other figures, except that the positioning lugs 26' and blade notches 30 are set so that its upper edge 29' does not touch the upper flange 22' of the plate 10'. Said upper flange 22' extends for the full length of the plate 10' thus projecting the entire length of the edge of the blade. The plate 10' might be designed for the blade 28' thus positioned on the plate 10' to be clamped thereon by a spring clamp handle as shown in Figures 1 and 2; but a still different method is illustrated in Figures 5, 6 and 7 wherein the plate 10' is represented as having a formation 42 of metal stamped in its midst, constituting a face groove, which is clearly seen in Figure 7, into which the part 34 of the handle can slide, and wherein it is held by the walls of the groove so that it cannot twist or slip sideways.

Other variations may be made in constructing the razor of the invention. It is a feature that the type of construction de-

scribed permits adequate strength of parts for firmly holding and conveniently operating the blade, while protecting its edge and particularly its corners; and that the only parts required are the handle and the guard 5 holder. These latter may be so small as to be substantially no greater in length and breadth over all than the blade itself; and ample strength is obtained if the bar 10 metal employed is only a quarter of an inch broad. As the guard 24 need not be so wide as this, it makes the whole, when the handle is removed and laid flat on the blade and plate 10, occupy a space under five-sixteenths of an inch thick, and barely larger than the blade. When placed in a suitable case these parts are an unappreciable burden to one who has occasion to carry them. The manufacture, at the same time, is so simple 15 that the whole may be inexpensive.

I claim as my invention:

1. A safety razor, having a blade; a guard plate, having a guard flange and means to hold the blade when the two are together; 25 and a handle, separable from both and adapted to engage the guard flange and to press together the plate and blade.

2. A safety razor, having a blade; a guard plate, having means to hold the blade without slippage when the two are together; and a handle, separable from both, and adapted to engage the plate at its top edge on one side of the blade, and to engage the plate at its bottom edge on the other side of the 35 blade, and to engage the blade at a location between said points of engagement, pressing the plate and blade together where it thus engages the blade.

3. A safety razor having a blade, a guard 40 plate with guard flange, and a handle adapted to hold said blade and plate together; said guard plate having an opening along one edge for exposure of the cutting edge of the blade, and having arms at the 45 sides thereof supporting the ends of the guard flange; there being a notch in said flange midway of its ends adapted to be engaged by the handle whereby the flange is maintained rigid.

4. A safety razor having a blade; a guard plate having a guard flange along its bottom edge integral therewith, bent from its plane substantially at right angles thereto and having a handle-engaging notch in its 55 edge most remote from said plane; and a handle, adapted to engage both the top edge of the plate and the notch in said flange, and arranged between said points of engagement to press said blade and plate together.

5. A safety razor, having a blade; a guard plate having means to hold the blade without slippage when the two are together; and a bent flat bar handle adapted to engage 60 the guard edge of the guard plate, and the top edge of the guard plate, and the middle

of the blade, thereby to press the blade and plate together and to be itself maintained in position.

6. A safety razor, having a blade; a guard plate having means to hold the blade without slippage when the two are together; and a handle, comprising a lever engaging the two edges of the guard plate, at one of which it is latched, and engaging the blade therebetween to press it against the plate. 70

7. A safety razor, having a blade; a guard plate having means to hold the blade without slippage when the two are together; and a handle comprising a lever engaging the two edges of the guard plate, at one of which the plate is yieldingly elastic and constitutes a latch engaging the handle; said handle having a part held by the latch in engagement with the blade to press it against the plate. 80

8. A safety razor, having a blade; a guard plate having a guard flange at its bottom, with a handle-engaging notch therein, and having a handle-engaging notch at its top edge; said guard plate and blade being 90 mutually adapted to prevent slippage of one on the other when they are together; and a handle adapted to compress the plate and blade together and to engage in said notches of the plate for attachment thereto. 95

9. A safety razor, having a blade; a guard plate; and a handle; all being made of sheet metal; the guard plate and blade being formed with mutually engaging notches and 100 projections to prevent the slippage of one on the other when they are together, and the handle being of relatively thick material bent to engage the two and hold them together.

10. A safety razor, having a flat blade; a plate of sheet metal having a smooth face and having on its back upstanding integral lugs adapted to position the blade thereon, and an integral flange, with slot, adapted to guard the cutting edge of the blade; and a 110 separable handle adapted to be hooked over the edges of the assembled plate and blade, compressing them together; the said parts being adapted when so hooked for the handle to be non-rotatable with respect to the 115 blade and plate.

11. A safety razor having a blade and a positioning plate therefor adapted to be held between the blade and the surface to be shaved and having an opening therein for exposing the cutting edge of the blade, combined with a handle adapted to secure the plate and blade together; said plate having a guard flange adapted to engage said surface to limit the approach of the cutting edge thereto, and being engaged by said handle whereby its position with respect to said surface and the blade is maintained. 120

12. A safety razor having a blade and a holder plate therefor, combined with a han- 130

dle adapted to secure them together; said handle extending, when in place, in a direction perpendicular to the cutting edge and looped back toward it in a plane perpendicular to it, whereby it may be grasped with finger pressure in a direction parallel to said edge.

13. A safety razor having a blade and a holding plate therefor with a guard flange
10 for the cutting edge of the blade arranged

in a plane approximating perpendicularity to the plane of the plate, combined with a handle adapted to secure the blade and plate together, and removable therefrom and adapted when removed to be packed in the 15 angle between the guard plate and said flange.

Signed at Boston, Massachusetts, this eighteenth day of April, 1921.

CHARLES S. PARKER.
